RAIL LUBRICATOR.

Application filed November 22, 1923. Serial No. 676,395.

This invention relates to improvements in lubricating apparatus, and has particular reference to a mechanism for lubricating railway rails.

5 It has heretofore been the general practice to apply a lubricant, such as a mixture of graphite and water, to rails by hand. This operation has been found to be exceedingly slow and expensive. Furthermore, 10 the graphite has a natural tendency to separate from the water, unless constantly stirred, and forms a sediment in the bottom of the receptacle in which the lubricant is carried, with the result that the solution 15 applied to the rails becomes very thin thereby causing the loss of considerable lubricant by dripping from the rails unless extreme caution is exercised in its application.

20 An object of the present invention is to overcome the present difficulties and provide an apparatus by means of which a lubricant may be rapidly and properly applied to a rail and constantly stirred or agitated to 25 prevent separation of the ingredients of the lubricant during its application.

Another object is to utilize the movement 30 of the apparatus on a rail to operate an agitator which will constantly keep the lubricant stirred while it is being fed to the rail.

35 A further object is to control from a common source the adjustment of the lubricant applying means with respect to a rail and the feeding of the lubricant to said means.

The above and other objects will appear 40 more clearly from the following detail description, when taken in connection with the accompanying drawings, which illustrate a preferred embodiment of the inventive idea.

In the drawings—

45 Figure 1 is a side elevation, partly broken away and shown in section, of the apparatus constructed in accordance with the invention; and

Figure 2 is a rear elevation thereof, partly broken away and shown in section.

In its preferred form the invention is 50 shown as comprising a base 3 having depending therefrom the front and rear hangers 4 and 5, respectively, the former of which support the roller or wheel 6, while the latter hangers support the shaft 7 upon which is rotatably mounted the roller 8. The

rollers 6 and 8 are grooved, as clearly indicated in Figure 2, to conform to the contour of the tread of the rail 9 which is to be lubricated, so that the apparatus will be guided in its movement over the rail. 60

Secured in any preferred manner on the base 3 is the lubricant containing receptacle 10 having an opening 11 in the top thereof for filling the receptacle with a lubricant, such as a mixture of graphite and water, 65 said opening being normally closed by a cover or closure 12. The base 3 also has attached thereto intermediate its forward and rear ends a handle 13 which is utilized to facilitate the transportation of the apparatus from place to place when not being used to lubricate a rail. Extending upwardly and rearwardly from the receptacle 10 are the opposed members 14 which terminate at 70 their upper ends in a handle 15 employed to 75 maintain the apparatus in a vertical position upon the rail 9 and propel said apparatus along the rail.

The bottom of the receptacle 10 adjacent the rear end and one side thereof is provided with an outlet opening 16 for the lubricant which is normally closed by a valve 17, the rod 18 of which is slidably mounted in a guide 19 secured to the bottom and rear end of the receptacle. A spring 80 85 20 is disposed between the upper end of the guide 19 and the valve 17 to exert a downward pressure upon said valve to maintain the same in its closing position. The upper end of the rod 18 projects through the top 90

95 of the receptacle 10 and has adjacent its upper extremity a laterally extending pin 21 designed to be contacted by the free end of an operating arm 22. This arm 22 is pivotally connected at its opposite end to a lug 23 extending upwardly from the top of the receptacle 10 so as to permit of a vertical movement of said arm to contact the free end thereof with the pin 21 and, consequently, move the rod 18 upwardly to open the valve 17. To accomplish this operation the operating arm 22 has connected thereto intermediate its ends one end of a flexible element 24, the opposite end of which is secured to a pin 25, the intermediate portion of the element 24 being passed around a series of guides 26 disposed between the members 14. The pin 25 is slidable longitudinally of the members 14 and mounted in a bearing 27 disposed between said members 110

and is provided at its upper end with a ring 28 which may be grasped by the operator to exert an upward pull upon the pin to actuate the operating arm 22.

5 An outlet pipe 29 is secured to the bottom of the receptacle 10 in communication with the outlet opening 16 and has its rear open end projecting beyond the rear end of said receptacle to receive the upper end of a coupling 30 which is slidably mounted upon the projecting end of said outlet pipe. Extending laterally from the upper end of the coupling 30 is an arm 31 to which one end of a coil spring 32 is secured, the other end 10 of said spring being fastened to the base 3, as clearly shown in Figure 2. The intermediate portion of the spring 32 is coiled about the upper end of the coupling 30 and by securing the spring as described, it will be obvious that the same will act to yieldingly maintain the coupling 30 in an inoperative position with its lower end spaced from the rail 9, as shown in Figure 2.

15 The lower end of the coupling 30 is provided with a laterally extending chamber 33 having communication with the body of the coupling through an opening 34. A brush 35 is mounted in the open end of the chamber 33 and has a pressure exerted 20 thereon by a coil spring 36 or other suitable means to yieldably maintain the bristles of the brush 35 in contact with the inner edge of the rail 9 to be lubricated. The lower end of the coupling 30 adjacent 25 the open end of the chamber 33 is provided with a lateral feed opening 37 which permits of the lubricant being fed directly to the free ends of the bristles of the brush 35 thus providing a supply of lubricant for 30 the brush in addition to that which flows through the opening 34.

The invention further contemplates the provision of means for moving the brush 35 into operative relation with respect to 35 the rail 9 simultaneously with the adjustment of the valve 17 to an open position. To this end the free extremity of the arm 31 has connected thereto one end of a coil spring 38, the other end of which has secured thereto one end of a flexible element 39 which is extended over the two uppermost guides 26 and attached at its upper end to the lower end of the pin 25 thus making the pin 25 a common means for exerting an upward pull upon both of the flexible elements 24 and 39. Upon actuation of the pin 25 as described, the valve 17 will not only be lifted to an open position, but an upward pull will be exerted 50 upon the free end of the arm 31 thus swinging the coupling 30 about its pivotal mounting upon the pipe 29 against the tension of the spring 32 so that the free end of the brush 35 will be brought into contact 55 with the rail 9. The lubricant flowing

through the opening 16 and from thence to the brush through the coupling 30 will be applied to the rail as the apparatus is moved along the latter. By introducing the spring 38 between the arm 31 and the flexible element 39 a yielding action will be effected which will prevent the brush 35 from coming into too close contact with the rail 9 regardless of the amount of pull exerted upon the pin 25 and in this manner the lubricant will be effectively applied to the rail. Upon release of the pin 25 by the operator it will be obvious that the valve 17 and coupling 30 will be restored to their normal positions by the action of 60 the springs 20 and 32, respectively.

The invention further provides means for constantly agitating the lubricant in the receptacle 10 during the operation of the apparatus so that the graphite and water 65 will be thoroughly mixed while the lubricant is being fed to the rail. This means preferably comprises an agitating blade 40 secured to a vertically arranged shaft 41 adjacent the lower end thereof, said shaft 70 being rotatably mounted in suitable bearings and having its upper end projecting beyond the top of the receptacle 10. The upper end of said shaft carries a bevel gear 42 meshing with a similar gear 43 secured 75 to one end of a transversely arranged shaft 44 rotatable in a suitable bearing 45 carried by the top of the receptacle 10. The end of the shaft 44 opposite that carrying the gear 43 projects beyond the adjacent 80 side of the receptacle 10 and carries a sprocket 46 around which extends a drive-chain 47, which is also engaged with a sprocket 48 carried by the shaft 7 so that as the apparatus is propelled along the rail 85 9 rotation will be imparted to the shaft 41 and consequently the blade 40 through the intermediary of the gearing described.

What is claimed is:

1. In a rail lubricating apparatus, a lubricant containing receptacle capable of moving along a rail and having an outlet opening, a normally closed valve for controlling the flow of lubricant through said opening, a pipe movable with respect to said receptacle and rail and having a laterally extending brush for applying the lubricant to the rail, means connecting the pipe and receptacle for conveying the lubricant to said pipe, means common to said valve and said pipe for opening said valve and moving said pipe into operative relation to said rail, and means controlled by the movement of said receptacle along said rail for agitating the lubricant in said receptacle.

2. In a rail lubricating apparatus, a lubricant containing receptacle capable of moving along a rail and having an outlet opening, a normally closed valve for controlling the flow of lubricant through said opening,

a pipe secured to the receptacle, a second pipe mounted to turn on the first, spring means for holding the second pipe normally in inoperative position on the first pipe, 5 flexible elements connected to said valve and said second pipe, and a sliding member to which the flexible elements are secured for simultaneously operating said flexible elements to open said valve and move said 10 pipe into operative positions.

3. In a rail lubricating apparatus, a lubricant containing receptacle capable of being moved along a rail and having an outlet opening, a coupling connected to said receptacle at one end and having communication with said opening and movable at its other end toward and away from said rail, said other end of the coupling having a laterally extending and communicating chamber and 15 a feed opening at one end of said chamber, a brush yieldably mounted in said chamber and extending beyond the same for contact with said rail, the extended portion of said brush being disposed in juxtaposition to 20 said feed opening, and means for moving said brush into operative position in contact with said rail.

4. In a rail lubricating apparatus, a recep-

tacle mounted on rollers to travel on a rail, a pipe below the receptacle and communicating with the receptacle, a valve controlling the communication between the receptacle and pipe, a second pipe mounted to turn on the first pipe and having a laterally extending chamber at its lower end, a 30 spring pressed brush in said chamber, a spring for holding the second pipe in inoperative position, and means for swinging said pipe into operative position.

5. In a rail lubricating apparatus, a receptacle adapted to travel on a rail and having an outlet opening, a pipe into which the outlet opening discharges, a spring pressed valve for controlling the outlet opening, a 40 flexible member connected with the valve, a second pipe mounted to swing on the first pipe and carrying a brush at its lower free end, a spring for holding the pipe in inoperative position, a flexible member connected with the second pipe for swinging it, 45 and a common operating member for both of the said flexible members, whereby upon operating the said members the pipe carrying the brush will be swung into operative position and the valve opened.
